UNITED STATES PATENT OFFICE.

WILLIAM ARTHUR SHAW, OF NOTTINGHAM, ENGLAND.

LOCKING BUCKLE.

SPECIFICATION forming part of Letters Patent No. 292,372, dated January 22, 1884.

Application filed October 16, 1883. (Model.) Patented in England January 6, 1883, No. 81.

To all whom it may concern:

Be it known that I, WILLIAM ARTHUR SHAW, of Nottingham, England, have invented new and useful Improvements in Buckle-Locks, (for which I have obtained a patent in Great Britain, No. 81, bearing date January 6, 1883,) of which the following is a specification, reference being had to the accompanying drawings.

Figure 1 is a front view of one of my improved buckle-locks, showing the lock-bolt forming a strap-tongue in a locked position. Fig. 2 is a front view, showing the bolt unlocked. Fig. 3 shows a lock in connection with a strap and locked secure. Fig. 4 is a side view of a buckle-lock with the swiveled lock-case opened out; and Fig. 5, a view similar to Fig. 1, with the face-plate of the lock-case removed, showing how the rigid bolt slides.

My improved buckle-lock consists of the following parts, namely: two side plates, A A, near the bottom ends of which is secured a strap-rod, B, round which one end of a securing-strap, F, is passed, and kept in position by stitching or riveting. In the upper ends of the plates is secured a rod forming a strap-rod and buckle-prong rod, C; or the side plates may be formed in one piece, as shown in the drawings. Below the prong-rod is a box or case, D, inclosing a locking device of any suitable construction, having one or more locking-bolts, E, each of which projects and forms a buckle-prong, said bolt being rigidly and immovably fixed to its carrying-shank, which is located within the lock-case, as in Fig. 5, the shank being projected and retracted to actuate the rigid bolt by a key inserted through a key-hole in the face-plate of the lock-case.

The lower edge of the case D, at each end, is provided with an axle-pin, or it forms axle-pins, each of which turns in bearings formed in the side plates. By such means, when the securing-strap F is placed round a bag, box, package, or other article, and the strap is adjusted in position, it can be locked and left secure until opened by the key.

I am aware that prior to my invention hinged tongues have been used in buckle-locks, the lock of which was in one piece with the buckle-loops; and I am also aware that a lock-case has been pivoted in the frame of a buckle and formed with a fixed tongue at its outer or free end to engage a strap, the bolts of the lock-case projecting through its sides to engage recesses in the side bars of the buckle-frame for holding the lock-case immovable; but such constructions do not constitute my invention.

What I claim, and desire to secure by Letters Patent of the United States, is—

The combination, with the buckle-frame, of the lock-case D, swiveled to swing within the frame, and having at its outer end a longitudinally-sliding rigid bolt, E, capable of being advanced to constitute the tongue of the buckle, and also serve to immovably secure the lock-case in the frame, substantially as described.

In testimony whereof I have hereunto signed my name in the presence of two subscribing witnesses.

WILLIAM ARTHUR SHAW.
